(57) **CLAIM**

The ornamental design of a wireless transmission station, substantially as shown and described.

DESCRIPTION

FIG. 1 is a back perspective (elevational) view of another embodiment of a wireless transmission station in accordance with the present invention.

FIG. 2 is a back view of the wireless transmission station in FIG. 1.

FIG. 3 is a left side view thereof.

FIG. 4 is a right side view thereof.

FIG. 5 is a bottom view thereof.

FIG. 6 is a top view thereof.

FIG. 7 is a front perspective (elevational) view thereof; and, FIG. 8 is a front view thereof.

The broken lines represent portions of the wireless transmission station that form no part of the claimed design.

1 Claim, 6 Drawing Sheets
